Filed Apr. 16, 1962, Ser. No. 187,815

4 Claims. (Cl. 179—1)

This invention relates to an intercommunication (intercom) system and more particularly to means for indicating the busy condition of a station in such a system. The present invention is limited to intercom systems wherein at least three stations, two of which are masters, are metallically interconnected by the system circuitry.

In the intercom art, it is well known that a so-called master station is a station which is associated with an audio frequency amplifier cooperating with a transducer which can function selectively as a speaker or transmitter, the master station also including suitable switching means for selecting a called station and also for determining the direction of transmission. While an intercom system embodying the present invention may include so-called remote stations (these simply consisting of a transducer), the present invention relies upon the fact that a busy remote station has connected thereto some other but busy master station.

In its more general aspects, the invention takes advantage of the marginal conductive characteristics of a gaseous conduction lamp generally designated as a neon light. Such lights contain spaced electrodes within a glass envelope and operating in an environment usually consisting of a rare gas such as neon, as one example. Such lamps break down and become conductive above predetermined voltage, which voltage may depend upon the particular type of lamp involved. Once such a neon lamp breaks down and has a gaseous discharge therein, the lamp will maintain the discharge providing the potential across the lamp terminals remains above a minimum value, usually somewhat below the initial breakdown potential. Such lamps exhibit a negative resistance characteristic and require conventional resistors as ballasts to permit the lamp to operate satisfactorily. The current required for maintaining a discharge in some of the small neon lamps now available may be measured in microamperes. Thus, as an example, small neon pilot lights available in the market will operate on potentials of the order of about 60 volts and currents of the order of about 30 microamperes.

While a system embodying the present invention can use electromagnetic devices such as relays, the cost of a relay having even good sensitivity is far greater than the cost of a simple neon lamp. At that, such a relay would require far more current than a neon lamp. While extremely sensitive relays could be used with currents in the microampere range, the cost and delicacy of such relays as compared to a small neon lamp would make it practically impossible to use.

The invention generally provides at each master station a source of electric current connected through a resistance network to the station indicating neon lamp. The source may be A.C., in which case rectifier and filter means (as a capacitor) are used. If D.C. is used, then no rectifier or filter are needed. Direct current connections from the network are provided to the station selector switch. Each master station is provided with similar hookups. When one calling master station has its station selector switch provide a communication channel to any called station (either master or remote) so that these two stations are communicating with each other, each resistance network at each of such busy stations (if both are masters) is unaffected. This will result in the sta-

2

tion neon light remaining in its normal condition (either on or off as desired). If the normal condition of such a neon light at a station is on, it can function also as a pilot light. Assume now that a calling master station is communicating with a called station (either master or remote) and a third station (master) is attempting to call either of these two busy stations. The third station (master) will have its station selector switch set so that the third station is a calling station and is metallically connected to another calling station. The invention provides that when two calling stations are connected, the resistance network at the third station is unbalanced and the neon light of that third station goes to an off-normal condition. This is true whether the third station (master) was calling the first or second station.

In order that the invention may be understood, it will now be disclosed in connection with the accompanying drawings wherein:

FIGURE 1 shows an exemplary system embodying the invention having three master stations and four remote stations.

FIGURE 2 shows a modification of the network and lamp wiring which may be used instead of the resistance networks and lamp wiring illustrated in FIGURE 1.

FIGURE 3 is a further modification showing the station wiring.

Referring first to FIGURE 1, three master stations A, B and C are illustrated. Since the wiring in each station is the same, it is necessary only to describe in detail the wiring at one station. Referring for example to station A, wires 10 and 11 are line wires connected to a suitable source of electric power such as, for example, a conventional 115 volt, 60 cycle line. In the system as illustrated, it is necessary that each station be connected in a similar manner with respect to polarity to the power line. Accordingly, wire 11 will be regarded as the common or so-called ground. Wire 10 has ON-OFF switch 12 connected thereto, the other terminal of this switch going to resistor 14. The circuit continues through resistor 14 to half wave rectifier 16, then on to junction point 17. Between junction point 17 and wire 11 there is connected filter capacitor 18. From wire 11 there is connected capacitor 21 shunted by resistor 22 going to bus wire 24. Junction point 17 is connected to one terminal of resistor 25, the other terminal of which is connected to junction point 26. Between junction point 26 and wire 24 is connected neon light 27. This neon light may be of the type available in the market as pilot lights, whose characteristics have been previously pointed out. Resistor 25 is quite a bit larger in value than resistor 22 and both of them together function as ballasts for lamp 27. As an example, for a conventional 115 volt line, resistor 25 may have a value of about one-third megohm while resistor 22 can be about .1 megohm.

Junction point 26 is connected to one terminal of each of resistors 29 and 30. The remaining terminal of resistor 29 is connected to switch point 31 forming part of Talk-Listen switch TLA. Talk-Listen switch TLA has seven movable contacts 32 to 38 inclusive. The seven movable contacts are all mechanically coupled together and can have one of three positions. The position illustrated in the drawings is the normal Standby position. The remaining two positions are respectively Listen and Talk. Thus for example, movable contact 32 cooperates respectively with fixed contacts 32S, 32L and 32T. The remaining movable contacts cooperate with correspondingly numbered fixed contacts. In practice, the Talk-Listen switch may be selectively moved to Standby, Listen or Talk position. Fixed contacts 32T and 35S are connected by wires to junction point 40. Junction point 40 is connected to

one terminal of center tapped winding 41 of audio frequency output transformer 42. Winding 41 has its lower terminal connected to junction point 43 which in turn is connected to fixed contacts 33T and 36S. Secondary winding 41 of transformer 42 has its center connected through resistor 45 to moveable contact 34 of the Talk-Listen switch. Resistor 45 will usually be small and can be reduced to zero value. Contact 34S is dead and contacts 34L and 34T are connected together to bus wire 24. Bus wire 24 is also connected to the center tap of winding 47 of audio frequency input transformer 48. Winding 47, which is the primary, has one terminal which is respectively connected to contacts 35T and 32L. Winding 47 has its bottom terminal connected respectively to fixed contacts 36T and 33L. It will be noted that fixed contacts 35S and 35L are connected together and that fixed contacts 36S and 36L are also connected together. Moveable contacts 35 and 36 are connected to the two terminals of the winding of transducer 49 which can function either as a speaker or as a transmitter. A simple form of such transducer is a conventional electromagnetic type speaker.

Transformer 48 has secondary winding 50 whose terminals are connected to the input terminals of a conventional audio frequency amplifier 51. The output of amplifier 51 is connected through channel 52 to primary winding 53 of output transformer 42.

No attempt is made to show the circuit details between the secondary of transformer 48 and the primary of transformer 42. It is necessary that some amplification be provided for voice currents fed into primary winding 47 of transformer 48 to provide amplified voice currents in secondary winding 41 of transformer 42. It is therefore understood that the showing with regard to the input and output of amplifier 51 is diagrammatic.

Station A has voice channel input terminals 55 and 56 connected respectively to fixed contacts 37T and 38T. Fixed contacts 37T and 38T are respectively connected by jumpers to fixed contacts 35S and 36S. Terminals 55 and 56 of station A are the master input terminals MI and are connected by wires 57 and 58 respectively to a pair of wires AL1 and AL2 forming part of a cable running between the various stations. As is well known in intercom systems, each station requires its own pair of wires as a communication input channel connecting all other stations which may want to call.

Station A is provided with station selector switch SSA having as many buttons connected to communication channels as there are stations to be called. For example, station selector switch assembly SSA has switch portion SSAC which can be used to select station C with A as the calling station. Similarly, switch portion SSAB will be used for selecting station B. Switch portion SSAR4 will be used to select remote station R4. Switch portion SSAR1 is connected to select remote station R1. Similarly, station B has its station selector switch SSB provided with corresponding switch portions, one of which is SSBR2 connected to remote station R2 and another is switch portion SSBR4 connected to remote station R4. Station C has its station selector switch SSC provided with switch portions SSCR3 and SSCR4 going to remote stations R3 and R4 respectively.

Referring back to station A, station selector switch SSA has each switch portion movable to the right for the purpose of selecting a station. For example, when switch portion SSAR1 is moved to the right, movable contacts 60 and 61 are moved to the right to bridge the respective contact pairs. Thus, fixed contact 62 is connected to one terminal of the line going to remote station R1. Similarly, fixed contact 63 is connected to the other terminal of R1. When movable contacts 60 and 61 are both moved to the right (they move simultaneously), contact 62 will be connected to fixed contact 64 while contact 63 will be connected to fixed contact 65. Top right contact 64 and the corresponding contacts in

5 the other switch portions are connected to wire 68 going to movable contact 32 of Talk-Listen switch TLA. The bottom right contact 65 and the other corresponding contacts for the remaining switch portions of selector switch SSA are all connected to wire 70 going to fixed contact 33 of Talk-Listen switch TLA. Wires 68 and 70 are also connected to fixed contacts 37 and 38 respectively of the Talk-Listen switch.

Remaining stations B and C are correspondingly wired as illustrated in FIGURE 1. Assuming that the various stations are energized insofar as input lines 10 and 11 are concerned, and assuming each station is in Standby condition, each neon light in each station will be on. Referring for example to station A, current will flow from wire 10 through closed switch 12 to junction 26 through lamp 27, thence through resistor 22 to wire 11. With the Talk-Listen switch in the Standby position as shown, and with station selector switch SSA as shown, there will be no other path for electric current except the one traced above. In fact, it makes no difference what the condition of Talk-Listen switch TLA is, the same situation will prevail so long as all switch sections of station selector switch SSA are open as shown.

Now let it be assumed that station A wants to call station B. At station A, selector switch portion SSAB is operated. This will connect station A to station B via line wires BL1 and BL2. Assuming that station B is not busy and has all its sections of its selector switch SSB in the open position and its Talk-Listen switch TLB in the Standby position, the potential at junction 26 of station A can appear at terminals 55 and 56 of station B. There will be no current path in station B from terminals 55 and 56 on the one hand and line 11 in station B on the other hand. Hence for all intents and purposes, lamp 27 will be in the same circuit as before and will continue to be on. At the same time, the corresponding lamp at station B will also be on. This will indicate to station A that station B is not busy.

When station A first selects station B by operating selector switch station SSAB, Talk-Listen switch TLA at station A will be at Standby. As soon as A sees that B is not busy, he moves his Talk-Listen switch TLA to Talk position. B will hear A at full volume. B will be at Standby position. Voice currents coming in at terminals 55 and 56 at B will be fed through switch contacts 35 and 36 at station B to speaker 49 at station B. As soon as B operates selector switch section SSBA to connect to A and moves Talk-Listen switch TLB (not shown) to Listen, the resistor networks for the neon lights at each station will be independently energized. Thus the neon lights will remain on as long as A and B communicate with each other. Switch TLB corresponds to switch TLA but is for station B. The same change is made for station C.

Now assume that C wants to talk to A who is busy with B. C first operates station selector switch SSCA while keeping Talk-Listen switch TLC (not shown) at Standby. With A busy, an alternative shunt circuit around neon light 27 for station C will be provided. This circuit may be traced as follows.

Beginning with station C, junction point 26, current can flow in parallel through resistors 29 and 30 in station C through wires 68 and 70 to selector switch portion SSCA, thence line wires AL1 and AL2 to terminals 55 and 56 of station A. From terminals 55 and 56, current can flow through switch contacts 35S and 36S and along the wires to junction points 40 and 43. It will be noted that the condition of Talk-Listen switch TLA at station A is not important so long as it is not in Standby condition. From junction points 40 and 43, current will flow through winding 41 of transformer 42 through the center tap to movable contact 34 of station A. From movable contact 34 current can continue through switch contacts 34L or 34T at station A to wire 24, thence through resistor 22

to wire 11. The resistance of this shunt path is low enough so that the potential between point 26 and wire 24 at station C drops due to the increased potential drop across resistor 25 at station C. The result is that neon light 27 at station C will go out.

In the assumed situation above where station A and station B are both interconnected and are both master stations, a similar shunt path can be traced through station B. If station A were connected with a remote station, such as for example R4, station C would get a busy signal if trying to select R4. This would happen for the reason that station C would be connected to station A through lines R4L1 and R4L2. Thus in reality, the condition of station A would be responsible for station C having the light go out when trying to get R4. It is of course possible for station C to proceed in spite of the busy signal and become a party to the A and B hookup.

Referring now to FIGURE 2, it is possible to reverse the action of the neon lights at any one or all stations. Thus in the system previously described, the neon light is normally on during Standby and during use. When a station is trying to call another station and finds it busy, the busy condition will be indicated by the light going out at the station trying to make a call. The modification illustrated in FIGURE 2 changes this arrangement so that the light is normally out but goes on to show that another station being called is busy. This modification is provided by the simple expedient of moving neon light 29 from the position illustrated in FIGURE 1 to the position illustrated in FIGURE 2. In this modified position, the neon light is connected in series between junction 26 and the adjacent terminal of resistor 25. Everything else will remain the same.

Referring now to FIGURE 3, a still further modification is shown wherein an isolation transformer is provided from line wires 10 and 11 and the remainder of the system. Isolation transformer 80 has primary winding 81 connected to supply wires 10 and 11 when switch 12 is closed. Primary winding 81 has the bottom terminal connected to wire 11 and also connected to conductor 24' through isolation resistor 83. Conductor 24' is equivalent to conductor 24 in FIGURES 1 and 2. The remainder of the circuit beyond lamp 27 in FIGURE 3 is the same as in FIGURE 1. Transformer 80 has secondary 84 connected in exactly the same fashion as in FIGURE 1. In this modified form illustrated in FIGURE 3, resistor 14 of FIGURES 1 and 2 may be provided ahead of rectifier 16 in FIGURE 3 or not. Resistor 14 limits surge current through rectifier 16 if such protection is desired. Instead, secondary winding 84 may serve to limit the amount of surge current drawn from wires 10 and 11.

In FIGURE 3, resistor 83 may be considered as equivalent to resistor 22 of FIGURES 1 and 2. The operation of a system utilizing this modification illustrated in FIGURE 3 is the same as described in connection with FIGURE 1. Resistor 83 provides the equivalent return path to common power line 11 as provided by resistor 22 in FIGURE 1. Hence when a busy circuit is selected, the D.C. return path will be similar to that described in connection with FIGURE 1. Stations using the arrangement of FIGURE 3 must be connected with proper polarity to the power line.

An intercom system may have station A wired as illustrated in FIGURE 1, station B wired as illustrated in FIGURE 2 and station C wired as illustrated in FIGURE 3. Any combination of modifications may be used.

In connection with resistors 29 and 30, it will be noted that these two resistors at a calling station are connected across secondary 41 of the amplifier output transformer at any called station. Because of this, it is desirable to have the values of resistors 29 and 30 (they should be equal) high enough so that secondary 41 of audio frequency transformer 42 at any called station will not be shorted. Secondary 41 of the transformer will have a low ohmic resistance for direct current. Insofar as re-

sitors 29 and 30 are concerned, each of these may have a value of substantially less than the value of resistor 22. Thus in the assumed example, details of which have been given before, resistor 22 may have a value of about 100,000 ohms and resistors 29 and 30 each may have a value of between about 30,000 and 40,000 ohms, although this value may be substantially greater or less as desired. The value of resistor 455 in the center tap connection can vary anywhere from zero up to about the same as each of resistors 29 or 30. In an actual example of such a system, filter capacitor 18 may be quite large and have a value of about 20 mfd. Capacitor 21 should be large enough to bypass audio frequencies and can have a value of about .05 microfarad. The remaining components such as transformers 42 and 48 will be conventional in the intercom art.

A master station embodying the present invention will have a ballast resistance network for a gas lamp energized from a suitable source of direct current. This ballast resistance network will also have resistors connecting a point on the ballast resistance network through a Talk-Listen switch in a Standby position to the line wires going from the calling station through a station selector switch to the appropriate line wires of a called station. This master called station will have its input line connected at all times across the secondary winding of its audio frequency output transformer. The center tap of this particular secondary output winding will be connected to bus wire 24 through a Talk-Listen switch only when the Talk-Listen switch is away from the Standby position. When such a master calling station is connected to a master called station by virtue of the operation of a station selector switch, and if the master called station is talking or listening, than the busy called station will provide a path in shunt to a portion of the gas tube normal resistance network. This shunt path will disturb the normal potential relationships which are present in the ballast network at the calling master station when such calling master station is not connected to any other station or is connected to some other station which is not busy. It is understood that this also applies when a connection is established to a remote station which happens to be busy with another master station. This is true, as has been previously pointed out, because of the hookup of the remote station to a master station.

A system embodying the present invention is highly advantageous insofar as reducing the number of interconnecting wires between stations is concerned. Between any two stations which are in communication with each other, there is provided a voice current channel (this consisting of a pair of wires between stations), this voice current channel also providing one-half of a signal channel for indicating a busy signal. Since the busy signal currents go the same direction in the two wires making up a voice channel, it is possible to arrange for these currents at a station to cancel out insofar as having any undesired effects in the voice communication channel is concerned. For signal purposes, however, the two wires making up a voice current channel cooperate with the common return of a power line energizing system for providing a signal channel. It is understood that every master station in a system embodying the present invention must be correctly connected to a common power energizing system so that the power line itself can function as part of the signal channel.

What is claimed is:

1. In an intercom system having a plurality of master stations interconnected by individual pairs of wires providing voice channels and having a common interstation ground separate from the voice channels, each master station having: an audio frequency amplifier having an output audio frequency transformer with its secondary winding connected at all times to its own voice channel input; a talk-listen switch having stand-by, talk and listen positions; station selector switch means for selecting an

outgoing line to a called station; a signalling system effective only on stand-by and, after selecting another station to be called, to determine if the called station is busy, said signalling system including; two equal load resistors connected only on stand-by through its talk-listen switch and through its station selector switch to a selected outgoing voice channel so that said two load resistors in series are connected across the secondary winding of the output audio frequency transformer of another master station; a source of direct potential connected between a high potential terminal and the common interstation ground; a gas tube having a breakdown potential lower than the direct potential available at the station; a two-part ballast resistor network for said gas tube; one such ballast resistor having one terminal connected to the high potential terminal of the voltage supply source; the other ballast resistor being smaller than the first one and having one terminal thereof connected to the interstation ground; a connection from the other terminal of the second ballast resistor to the center of the output transformer secondary winding through its talk-listen switch only when said talk-listen switch is off stand-by; and circuit connections involving the other terminals of the ballast resistors, the gas tube terminals and the common terminal of the load resistors and completed by its talk-listen switch at stand-by only and the talk-listen switch at a connected different master station for determining whether the gas tube at a

5

10

15

20

25

calling master station is on or off; said two conditions being determined by whether the talk-listen switch at a connected master station is on stand-by or off stand-by; said gas tube condition indicating busy or idle status of any called station.

2. The system according to claim 1 wherein the connection between the secondary winding center tap and the other terminal of the second ballast resistor includes a resistor whose value is smaller than any of the previously identified resistors.

3. The system according to claim 1 wherein said gas tube is connected between the other terminals of the two ballast resistors and wherein said other terminal of the first ballast resistor is connected to the junction of the two load resistors.

4. The system according to claim 1 wherein said gas tube is connected between the other terminal of the first ballast resistor and the common terminal of the two load resistors and wherein the other terminal of the second ballast resistor is connected through the talk-listen switch to the center tap of the output secondary winding only when the talk-listen switch is off stand-by.
